(57) **CLAIM**

The ornamental design for an exoscope illuminator, as shown and described.

DESCRIPTION

FIG. 1 is a front perspective view of an exoscope illuminator according to the present invention.

FIG. 2 is a front view of the exoscope illuminator of FIG. 1.

FIG. 3 is a rear view of the exoscope illuminator of FIG. 1.

FIG. 4 is a left side view of the exoscope illuminator of FIG. 1.

FIG. 5 is a right side view of the exoscope illuminator of FIG. 1.

FIG. 6 is a top view of the exoscope illuminator of FIG. 1; and,

FIG. 7 is a bottom view of the exoscope illuminator of FIG. 1.

The dashed lines illustrate environment that does not form a part of the present invention, and no claim is made to the material illustrated with dashed lines.

The exoscope illuminator is shown with symbolic breaks. The appearance of any portion of the article between the break lines forms no part of the claimed design.
